UNITED STATES PATENT OFFICE.

GEORGE THOMAS LEWIS, OF MIDDLEVILLE, NEW YORK.

SPLIT PISTON FOR INTERNAL-COMBUSTION ENGINES AND ANALOGOUS USES.

Application filed September 19, 1922. Serial No. 589,096.

To all whom it may concern:

Be it known that I, GEORGE T. LEWIS, of Middleville, in the county of Herkimer, in the State of New York, have invented new and useful Improvements in Split Pistons for Internal-Combustion Engines and Analogous Uses, of which the following, taken in connection with the accompanying drawings, is a full, clear, and exact description.

10 This invention relates to sectional pistons for internal combustion engines and analogous uses where it is desired to maintain close fitting joints between the piston and bore of the cylinder for maximum compression and suction, according to the use to which the piston is put.

20 The main object is to provide a two-piece piston of this character divided longitudinally in such manner that the opposed sections may slide telescopically one upon the other under the action of expanding springs to automatically compensate for wear and thereby to effect a close running joint between the piston and bore of the cylinder.

25 Another object is to bring the telescoping parts of the sections close to the head of the piston so that the overlapping portions may strengthen the head and impart the desired axial rigidity thereto for resisting the strains 30 incidental to compression and expansion of the explosive mixture and at the same time holding the sections in fixed axial relation while permitting their lateral expansion under the tension of the springs.

35 Other objects and uses relating to specific parts of the piston will be brought out in the following description.

In the drawings:

40 Figures 1, 2 and 3 are respectively a top plan, an inverted plan and a side elevation of a piston embodying the various features of my invention.

Figure 4 is a longitudinal sectional view taken on line 4—4, Figure 1.

45 Figure 5 is a transverse sectional view taken on line 5—5, Figure 2.

Figures 6 and 7 are perspective views of opposite halves of the piston.

50 As illustrated, this piston is made in two parts, or substantially semi-cylindrical half sections —1— and —1'—, in so far that the major portion of the length of the piston is divided diametrically at —2— from its inner end to within a relatively short distance from the outer end or head where the division line is offset to opposite sides of the

plane of diametrical division. That is, the head end of one section, as —1—, is provided with a flange or tongue —3— extending to one side of the division line —2—, and is 60 also provided with a recess or groove —4— extending to the opposite side of the diametrical division line, while the head end of the other section, as —1'—, is provided with a recess or groove —5—, extending to the 65 same side of the division line —2— as the tongue —3—, and is also provided with a flange or tongue —6— extending to the opposite side of said divisional line, in the plane of the groove or recess —4—. 70

The recesses or grooves —4— and —5— therefore extend in opposite directions from the diametrical division —2— at right angles thereto, so that the top wall of the recess —5— will be coincident with the bottom wall of the recess —4—. 75

In like manner the flanges or tongues —3— and —6— extend in opposite directions from the diametrical division —2— at right angles thereto, so that the inner face 80 of the flange —6— will be substantially coincident with the outer face of the flange —3—. The thickness of the flange —3— is substantially equal to the axial depth of the groove or recess —5—, while the thickness 85 of the flange —6— is substantially equal to the axial depth of the recess —4—, which brings the outer end faces of both piston sections in substantially the same plane at right angles to the axis of the piston, while 90 the transverse width of the flange —6— will be substantially twice the width of that of the flange —3—, and in like manner the transverse width of the groove —5— will be approximately half the width of the groove 95 —4—.

The outer edges of the flanges —3— and —6— and corresponding bases of the grooves —4— and —5— are substantially straight and parallel, and by reason of the fact that 100 they extend in opposite directions beyond the axis of the piston and also beyond the diametrical division —2—, it is evident that the lengths of the outer edges of said flanges are less than the diameter of the piston in 105 that they terminate in the periphery thereof.

By dividing the piston longitudinally in the manner just described, the flange —3— of the section —1— will overlap a portion of the section —1'— at one side of the axis 110 of the piston, while the flange —6— of the section —1'— will overlap upon the section

—1— at the opposite side of said axis, thereby establishing what may be termed an interlocking tongue and groove connection between the head ends of both sections and 5 permitting those parts to slide transversely one upon the other.

- The intermediate portions of the sections —1— and —1'— are provided with diametrically extending openings —7— at 10 right angles to the plane of division —2— and parallel with the flanges —3— and —6—, some distance inwardly beyond said flanges for receiving the opposite ends of a coupling pin —8—, which in turn is adapt- 15 ed to receive the adjacent end of a suitable connecting rod or pitman by which the piston is connected to the crank shaft of the engine in the usual manner not necessary to herein illustrate or describe.
- 20 One end of the coupling pin —8— may be secured against axial movement to the adjacent piston section, as —1'—, by means of a set screw —9—, while the opposite end extends loosely into its bearing —7— in the 25 corresponding piston section to permit the piston sections to slide or expand laterally relatively to each other.

Suitable means is provided for yieldingly urging the piston sections against the side 30 walls of the bore of the cylinder, and for this purpose a pair of light coil springs —10— are arranged in transversely extending sockets —11— in one of the piston sections, as —1—, preferably in the flange 35 —3—, so as to bear against the base of the groove —5— of the opposed section —1'—.

It is evident, however, that suitable springs may be placed in other relations between the piston sections for expanding said 40 sections against the walls of the cylinder and therefore I do not wish to limit myself to the precise location and construction of the springs.

The periphery of the piston may be provided with one or more annular grooves, as 45 —12— and —12'—, located preferably above and beneath the coupling pin —8— for receiving any suitable form of piston rings not shown and not necessary to herein illustrate and describe, since the use of piston 50 rings is well known. It is desirable, however, to make the upper groove —12— of sufficient length axially to receive a pair of piston rings arranged edge to edge for reducing the liability of leakage of gas or 55 oil from or to the combustion chamber.

As previously stated, the edges of the flanges —3— and —6— are straight and parallel with the diametrical division —2—, and by constructing said flanges so 60 that the flange of each section will overlap upon portions of the other section, adds strength to the head of the piston to resist the strains incidental to compression and expansion of the exploded gases and also 65 reduces the liability of leakage at the joints, and the flange of each section forms a guide for holding the sections against relative axial movement while permitting their relative transverse movement. 70

What I claim is:

1. A piston composed of opposite sections, a coupling pin extending diametrically through both sections at substantially right angles to the plane of their meeting edges, 75 the meeting sides of the head end of each section being provided with a laterally projecting tongue and a groove, the tongue of each section being slidable in the groove of the other section. 80

2. A piston composed of opposite sections, a coupling pin extending diametrically through both sections at substantially right angles to the plane of their meeting edges, 85 the meeting sides of the head end of each section being provided with a laterally projecting tongue and a groove, the tongue of each section being slidable in the groove of the other section, and means for exerting radial pressure upon both sections in the direction of the axis of the coupling pin. 90

3. A piston comprising opposed sections having aligned radial openings between their ends, a coupling pin inserted in said openings and extending diametrically of the piston at right angles to the meeting faces of the sections, each section having a tongue and a groove extending radially from said meeting faces in the direction of the axis of the coupling pin, the tongue of each section 100 being slidably engaged in the groove of the other section, the edges of the tongue and bases of the grooves being substantially straight and disposed at right angles to the axis of the coupling pin. 105

In witness whereof I have hereunto set my hand this 9th day of September, 1922.

GEORGE THOMAS LEWIS.
